SHEET GAUGE

Original Filed March 17, 1930

UNITED STATES PATENT OFFICE

JAMES FLOCKHART, OF SAN FRANCISCO, CALIFORNIA, ASSIGNOR TO THE FLOCKHART CO., OF SAN FRANCISCO, CALIFORNIA, A CORPORATION OF CALIFORNIA

SHEET GAUGE

Application filed March 17, 1930, Serial No. 436,502. Renewed May 24, 1932.

This invention relates to improvements in sheet gauges, and more particularly to a combined sheet gauge and gripper for printing machines.

5 Among the objects of the invention is to facilitate the placement of the sheet gauges on the platen, with respect to the form or stencil in printing machines.

Another object is to combine a paper gripper with the sheet gauge to hold the paper against shifting during the printing, embossing and stamping operation. Other objects and advantages will appear as the description progresses.

15 A further object is to provide a combined sheet gauge and gripper which may be depressed below the plane of the platen.

In this specification and the accompanying drawing, the invention is disclosed in its preferred form. But it is to be understood that it is not limited to this form because it may be embodied in other forms. It is also to be understood that in and by the claims following the description it is desired to 25 cover the invention in whatsoever form it may be embodied.

Broadly stated, the invention consists in combining the sheet gauges and depressible sheet grippers in a plate which may be adjustably attached to the platen or bed of the printing machine.

In the one sheet of drawing:

Fig. 1 is a fragmentary plan view from above of a combined sheet gauge and gripper 35 in a plate applied to a platen in accordance with this invention.

Fig. 2 is an enlarged detail in longitudinal vertical section on the line II—II, Fig. 1, of the gripper-gauge in the normal position.

40 Fig. 3 is a similar view of the same in the operative position.

Fig. 4 is a similar view on the line IV—IV, showing one manner of adjustably fixing the 45 plate to the platen.

In detail the construction illustrated in the drawing comprises the gauge plate 1, having the throats 2, and the sockets 3, therethrough. The slots 4 extend laterally through the plate 50 from the edge of the holes. The grooves 5,

lead from the sockets 3 into the slots 4 in the underside of the plate.

The gauge consists of the head 6, preferably semi-circular, to fit freely within the throat 2. This head is squared vertically on its diameter at 7 parallel with the adjacent edge of the plate 1.

The head 6 is mounted on the spring wire stem 8, which extends through the slot 4, into the groove 5, and is bent upward to form a 60 pin 9 engaging in the socket 3.

This stem is held securely in position in the plate by the frictional engagement of the pin and socket 9—3, but may be removed by grasping the head 6 and moving it downward 65 parallel with the axis of the pin 9. These gauges are securely held in operative position when the plate rests upon the platen or bed 10.

In silk stencil printing apparatus the 70 platen 10 is preferably composed of non-warping wood veneer panel, in which case the plate 1 can be adjustably secured thereto by the thumb tacks 11, passing through the countersunk holes 12 in the plate, the heads 75 of the tacks being flush with the top plane of the plate 1. On metal platens the plate 1, can be slotted at intervals along its margins to engage cap screws threaded into the platen 10. The plate 1 can be attached in 80 any manner best suited to the conditions to be met, by those skilled in the art.

The plate 1, functions as the top surface of the platen, and is preferably composed of metal to withstand the pressure in printing 85 presses. For the stencil printing apparatus, where there is little or no pressure, aluminum is desirable because of its lightness.

The gauges are arranged along two sides of the plate 1, on lines exactly 90 degrees to 90 each other or at right angles to the edges of the sheet 13, resting upon the plate, see dotted lines, Fig. 1.

Heretofore it has been the practice in the printer's art to cover the platen with a sheet 95 of paper attached thereto, then stick pins through the paper or paste guides thereon, against which the sheet can be alined for registration with the printing form or stencil. The placement of individual gauge pins or 100

guides, as previously practiced, is a tedious labor and time wasting operation.

It is necessary to guide only two edges of the sheet, irrespective of its size or shape. 5 This is provided for in the present invention by the longitudinal row of guides 6 at the left side and the lateral row of similar gauges at right angles thereto at the rear of the plate 1. It is obvious therefore that the single operation of adjusting the plate 1 on the platen 10 adjusts all the gauges and assures the proper placement of the sheets, preceding the printing operation.

In the prior practice described, it is also 15 necessary to place the pins or guides lateral to the area of the type form or stencil so as not to injure the same or interfere with its impression. In the present instance the gauges 6 mounted upon the spring wire stems 20 8 depress into the throats 2 if so located that they come within the margin of the form or stencil. This is particularly valuable in the latter case, since the stencil being of fragile silk cloth, such as bolting cloth, would 25 be injured or the impression marred if the guide did not give way under pressure.

In the economical use of the stencil it is often desirable to distribute several "jobs" or impressions throughout the area of the 30 stencil. This requires that the gauges be within the area of the stencil impression. This is possible by the use of this invention without danger to the texture of the stencil.

By the thumb tack 12 adjustment, guiding 35 the sheets to insure perfect registration, consecutive color impressions on a single sheet can be quickly accomplished after changing the stencils for each color "block" or area.

It is equally important to grip the edge of 40 the sheet to prevent it shifting prior to or during the printing operation. This is accomplished by the gripper lug 14 on the head 6 overhanging the edge 7, and adapted to spring the margin of the sheet 13 down into the throat 2, and clamp the sheet in adjusted 45 position, see Fig. 3.

This depression of the heads 6 occurs when 50 the surface of the stencil or any part of the frame, such as 15, descends upon them. The upper surface of the heads 6 should be slightly convex to protect the stencil.

The number of gauges used in either or both 55 series will depend upon the size of the sheet 13 or the amount of gripping necessary to prevent it from shifting.

Having thus described this invention, what I claim and desire to secure by Letters Patent is:

1. A sheet gauge comprising a plate having 60 therein a throat and a socket joined by a slot, a guide movable in said throat and mounted upon a spring stem extending into said slot and engaging said socket.

2. A sheet gauge comprising a plate having 65 openings therein, resilient guides in said

openings having grippers thereon coacting with the edge of said openings.

3. A sheet gauge comprising a plate having 70 openings therein arranged along two edges thereof, resilient guides in said openings, and grippers on said guides coacting with the edges of said openings.

4. A sheet gauge comprising a plate having 75 arranged along two edges thereof throats and sockets joined by slots, guides movable in said throats and mounted upon spring stems extending into said slots and engaging said sockets; and grippers on said guides coacting with the edges of said throats.

5. A sheet gauge comprising a plate having 80 throats therein, resilient guides in said throats, a platen, countersunk attaching means in said plate detachably engaging said platen.

In testimony whereof I have hereunto set 85 my hand this 10th day of March, 1930.

JAMES FLOCKHART.
